HOSIERY MEASURING DEVICE

Paul Verdier, San Francisco, Calif.

Application December 23, 1935, Serial No. 55,737

10 Claims. (Cl. 33—8)

This invention relates to a device for determining the correct length of hosiery for wearers, and has for its objects the provision of a simple device for accurately and quickly determining, in advance of a fitting, the correct length, in inches or other arbitrary scale, of hose required for legs of various sizes.

Other objects and advantages will appear in the following specification and drawing attached thereto.

In the drawing, Fig. 1 is a side elevational view of one form of my device.

Fig. 2 is a front elevational view of the device of Fig. 1.

Fig. 3 is a sectional view taken along the line 3—3 of Fig. 1.

Fig. 4 is a sectional view taken along the line 4—4 of Fig. 1.

Fig. 5 is a sectional view taken along the line 5—5 of Fig. 1 showing a portion of a shoe and leg of a person in dotted line.

Fig. 6 is a side elevational view of another form of my invention showing a shoe and leg of a person in dotted line.

Fig. 7 is a plan view of the upper end of the device of Fig. 6.

Fig. 8 is a sectional view taken along the line 8—8 of Fig. 6.

Fig. 9 is a sectional view taken along the line 9—9 of Fig. 6.

Fig. 10 is a fragmentary rear elevational view of the upper end of a portion of Fig. 1.

Fig. 11 is a fragmentary view of a portion of the device of Fig. 6 as seen in elevation.

Fig. 12 is a fragmentary view of a portion of the device of Fig. 6 as seen in elevation.

Fig. 13 is a fragmentary view of a portion of the device of Fig. 6 as seen in elevation.

Briefly described, heretofore hosiery for women has been supplied according to the size of the foot and in different lengths for each foot size. All stockings are more or less elastic, according to the type of weave and whether loosely or tightly woven.

Also some manufacturers incorporate elastic thread into the stocking adjacent the upper end so as to permit elasticity between the less elastic lower portion and the proper point of attachment of the garter. Obviously, if the stockings are too long, they must be folded over

and the greater the strain on the lower less-elastic portion. If the stockings are too short, the strain is excessive due to the fact that the elastic limit of the stockings is approached before engagement with the garters.

In view of the fact that a stocking when on the

wearer will vary as to the height it reaches on the leg in proportion to the circumference of the calf, the problem of supplying a proper length stocking to a customer purchasing the stockings has not heretofore been solved insofar as I am aware. Obviously, it would be prohibitive to permit a customer to try on three or four different sizes before buying, even if the customers were willing.

I have discovered that there is a definite relation between any given stocking construction and the circumference of a wearer's calf whereby it is possible to determine the degree to which such stocking will shorten in height, when on the leg, below its normal length before fitting. The practical adaptation of this relationship to a scale device whereby the correct length of stocking is quickly determined in advance of a fitting for persons having calves of varying sizes comprises my invention.

In detail, my device, as shown in Figs. 1 to 5 and 10, comprises an upright, flat-sided stick 1 of approximately 36 inches in length whereby it will extend from about the floor to appreciably above the knee of a wearer. A foot member 2 is secured to said stick at its lower end and projects at right angles from a side thereof, said member being formed at 3 to snugly fit across and against the instep of a shoe 4 that is provided with a heel 5 without removing the shoe from the wearer and when the wearer is in standing position. See Fig. 5.

Below the foot member 2 is a base 6 adapted to rest on the floor, and said base and foot member are connected at their opposite ends by bolts or pins 7 for slideable movement of the foot member toward the base, and coil springs 8 are interposed between the foot member and base normally tending to yieldably force the foot member and base apart to the limits of heads 9 of the bolts 7. These bolts are secured to the base at their lower ends and loosely pass through foot member 2 at their upper ends with the heads 9 on the bolts preventing separation of said member and base.

The foregoing construction insures the foot member positively engaging against the instep of the shoe, below the wearer's instep, irrespective of the height of the shoe heel while permitting the wearer to stand firmly and normally on the floor.

The upright stick 1 is vertically grooved at 10 along opposite edges and a gauge 11 formed with ears 12 (Fig. 3) that engage in said grooves respectively is positioned on the side of the stick from which the foot member 2 projects. Said

gauge and ears are elongated vertically so as to provide a firm bearing surface on the stick and at the lower end of the gauge a horizontally disposed yoke 13 projects outwardly, which yoke 5 is formed at its outer end to generally conform to the horizontal contour of the leg of a person at a point above the knee. A spring detent member 14 is carried on one side of the gauge and is normally adapted to frictionally engage an edge 10 of the stick to hold the gauge in any adjusted position, said detent projecting outwardly of the side of the gauge at one end for pressing against a spring to release the detent from engagement with the stick.

15 On the side 1' of the stick opposite said gauge the stick may be graduated in inches as indicated in Fig. 10, commencing from the upper surface of the foot member 2 at the point where the member engages the instep, and the inch marks 20 being indicated with the regular indicia. On the opposite side of the stick from the aforesaid graduations, are three vertically extending scales 15, 16, 17, of horizontal vertically spaced graduations 18 shown in the drawing as spaced an inch apart, 25 each scale commencing at its lower end at the point opposite the twenty-one inch graduation on the inch scale or the equivalent distance from the foot member 2 in case the inch scale is not used.

30 The scale 15 is headed at its upper end with the figure "12½" and the letter "S—" thus designating the scale as relating to a 12½ inch calf or less, which is small in size. The scale 16 is headed "13" and "M", indicating its reference to a "medium" calf of about 13 inch circumference. The scale 17 is headed "13½" and "L+" thus referring to a calf of from 13½ inch upward in circumference, or "large". These headings may 35 obviously be varied and still convey the same 40 import.

In operation, the wearer merely places her foot over the foot member 2 with said member under the instep of the shoe and the gauge 11 is slipped along the stick to the height along the upper leg 45 indicated by the wearer as being the length stocking desired. If the calf circumference is 13 inches or a fraction less than ½ inch more or less, the scale 16 will indicate immediately a figure, say "27", as shown in the drawing, indicating 50 that in order for the stocking to reach that height when fitted, a 27 inch length stocking will be necessary, although the actual length from the instep to said height is only 23 inches. Of course, this particular scale would be for the particular 55 type of stocking desired, and the indicia 18' would accordingly be modified as to weave, etc., and the scale for another type of stocking might indicate 26 inches. But the relationship of a greater length than the actual length from the 60 instep to the desired height would always exist. The inch scale on one side of the stick facilitates the use of the device for measuring the stocking to give the proper length.

In Fig. 6 I show another form of device in 65 which this upright stick is constructed of two lengths or pieces of telescopic square tubing, in which an upper piece 20 telescopes into a lower piece 21. The lower piece has a foot member 2', formed to snugly engage across the instep of the 70 shoe, secured rigidly to its lower end and extending laterally to one side with the outer end of the foot member turned up at 21 to insure proper positioning of the foot. The upper piece 20 is graduated on three sides, 22, 23, and 24, 75 with graduations corresponding to scales 15, 16,

17, respectively, except that the scale is inverted and the numerals on each scale become greater in descending along the piece instead of becoming greater as the scales ascend.

At the upper end of piece 20 a yoke 25 is provided resembling yoke 13 but much closer to the stick so as to not interfere with the leg of the person being measured. Fig. 6 shows in dotted line, a leg L as seen from the rear, in position for 10 measuring.

In the form of device shown in Fig. 6, the reading of the graduations on piece 20 is made at the upper end of the lower piece 21, and to facilitate the sliding of piece 20 relative to the piece 21, a thumb screw 26 may be provided on the outer 15 end of a stud bolt 27 that is secured at its inner end to the lower end of piece 20, said stud bolt being slidable in a vertical slot formed in the side of the piece 21. Upon tightening the nut, the pieces 20, 21 will then be positively locked in 20 any desired position. However, the frictional resistance between the two pieces 20 and 21 is ordinarily found to be sufficient to secure them against accidental movement relatively.

Enclosed within the lower end of piece 21 is a 25 coil expansion spring 27 adapted to react between a pin or stop 28 at its upper end secured to piece 21 and the upper end of a square rod or piece of square tubing 29 telescopically fitted in the lower end of said piece. Said square rod 29 30 is provided at its lower end with a base plate 6' extending below foot member 2' for resting on the floor. It will be seen that upon the foot of the wearer being positioned over the foot member 2' as in Fig. 6 the foot member is free to be 35 yieldably forced downward to accommodate any height of heel on the shoe, and the foot member 2' will always snugly engage across the instep of the wearer. Since the foot member is fixed relative to the upper end of the outer telescopic 40 tubing 21, the reading at the upper end of said tubing will be uniform and correct at all times. If desired, of course, regular inch graduations and indicia may be provided on the side of the 45 telescopic tubing 20 adjacent the leg of the wearer, whereby the scale can readily be used to measure the length of the hose to correspond to the indicia on the other side or sides of tubing 20.

It is, of course, manifest that a cushion of 50 sponge rubber may be used in place of the springs 8 and 27 positioned below and secured to the foot members 2, 2', and the base plates 6, 6' removed, but the springs are preferable. Also, instead of telescopic tubing, other telescopic 55 forms may be used, or pieces sliding side by side in guides, but the square tubing is the preferred form. Other minor variations may also be made in construction without departing materially from the invention, and the claims appended 60 hereto are intended to cover such other forms as may come within the spirit of the invention.

In order to insure the rod 29 against separation from the tubing 21, I provide a slot 30 alongside the spring 27 in which a pin 31 secured to the upper end of rod 29 is adapted to slide. The spring 27 will, of course, normally force the rod 29 outwardly to the distance permitted by the lower end of slot 30.

Having described my invention, I claim:

1. A device for use in determining proper hosiery lengths for a wearer comprising upper and lower vertically extending elongated strips secured together for sliding relatively in opposite vertical directions, the lower strip being provided 75

with a lateral projection at its lower end and the upper strip being provided with a member extending from a side thereof over the lower projection, said lower projection formed to engage 5 across the instep of the shoe of the wearer and means below said lower projection arranged and adapted to react between the floor and said projection to yieldably urge said projection upwardly against the instep of the shoe when the shoe is on the floor and the 5 device is in operative position with the strips extending alongside the wearer's leg, said strips comprising telescopic tubing with the upper strip sliding within the lower strip.

10 on the floor and the device is in operative position with the strips extending alongside the wearer's leg.

2. Apparatus of the character described comprising an elongated device adapted to extend 15 vertically alongside the leg of a person from the foot to a point above the knee, a member at the lower end of the device formed to engage below the instep of the foot, means at the upper end of the device vertically adjustable to various 20 points of elevation above the knee, scale indicia including gradations on said device indicating the degrees of modification in the length of a stocking before and after the stocking is fitted on the leg relative to the thickness of the leg 25 upon movement of the adjustable means to various points of elevation above the knee, and a base at the lower end of the device yieldably supporting said member spaced above the floor whereby said member is yieldably urged upwardly 30 at all times toward the instep of the foot.

3. Apparatus of the character described comprising an elongated flat-sided member adapted to extend vertically alongside the leg of a person substantially from the foot to a point above the 35 knee, means slidably mounted on said member for vertical movement and projecting laterally from a side of said member, scale indicia including gradations on one side of said device indicating the degrees of modification in the length of a stocking before and after the stocking is fitted on the leg relative to the thickness of the leg upon movement of the slidably mounted means to various degrees of elevation, means for positioning said device at its lower end in fixed relation to the foot of the person and means yieldably supporting said last mentioned means a distance above the floor.

4. Apparatus of the character described comprising an elongated flat-sided device adapted to extend vertically alongside the leg of a person substantially from the foot to a point above the knee, means slidably mounted on said member for vertical movement and projecting laterally from a side of said device, scale indicia including gradations on one side of said device indicating the degrees of modification in the length of a stocking before and after the stocking is fitted on the leg relative to the thickness of the leg upon movement of the slidably mounted means to various degrees of elevation, means for positioning said device at its lower end in fixed relation to the foot of the wearer, and said slidably mounted means being formed at its outer end to fit against the side of the leg of the person and to generally follow the cross sectional contour of the leg in shape.

5. A device for use in determining proper hosiery lengths for a wearer comprising upper and lower vertically extending elongated strips secured together for sliding relatively in opposite vertical directions, the lower strip being provided with a lateral projection at its lower end and the upper strip being provided with a member extending from a side thereof over said projection, said projection being formed to engage the in-

step of the shoe of the wearer and means below said projection arranged and adapted to react between the floor and said projection to yieldably urge said projection upwardly against the instep of the shoe when the shoe is on the floor and the 5 device is in operative position with the strips extending alongside the wearer's leg, said strips comprising telescopic tubing with the upper strip sliding within the lower strip.

6. A device for use in determining proper hosiery lengths for a wearer comprising upper and lower vertically extending elongated strips secured together for sliding relatively in opposite vertical directions, the lower strip being provided with a lateral projection at its lower end and the 10 upper strip being provided with a member extending from a side thereof over said projection, said projection being formed to engage the instep of the shoe of the wearer and means below said projection arranged and adapted to react between the floor and said projection to yieldably urge said projection upwardly against the instep of the shoe when the shoe is on the floor and the 15 device is in operative position with the strips extending alongside the wearer's leg, said strips comprising telescopic tubing and said means including a base plate having a vertically extending member telescopically slidable within the lower end of said lower strip, a stop within said lower strip and a spring engaging between said strip 20 and said member tending to urge the latter outwardly of the strip.

7. A device for determining proper hosiery lengths comprising a vertically extending element adapted to extend alongside the leg of a wearer 35 from the foot upwardly, a lateral projection at the lower end of said strip formed to engage the instep of the shoe of the wearer, a gauge member slidably mounted on said strip for sliding vertically to various points of elevation above the 40 wearer's knee when said projection is engaged across the instep of the shoe, a base member below the projection at the lower end of said element and lower projection and means for tending to urge said projection and element upwardly 45 when the base plate is on the floor.

8. Apparatus for use in determining hosiery sizes for legs of various thicknesses prior to fitting the hosiery on the legs comprising an elongated device adapted to be disposed vertically alongside 50 the leg to be fitted with the lower end of the device in fixed position adjacent the foot of the leg, a plurality of rows of indicia in side by side relationship inscribed on the device with the rows extending longitudinally thereof, the indicia 55 in the rows respectively being in terms of different sizes of hose, other indicia inscribed on the device in terms designating different leg thicknesses respectively disposed to identify the individual rows of indicia, said device including a member movable longitudinally therefore relative to the lower end thereof to various points of elevation along the leg above the knee thereof, means arranged and adapted to successively facilitate the reading of the indicia of the several 60 rows at a reading point as said member is moved, the indicia at said reading point in any one of the several rows designating the correct size hose for terminating at its upper end at the elevation of said member after the hose is fitted on a leg 70 the thickness of which is identified by the indicia that identifies the row in which the reading is taken as to leg thickness.

9. In a construction as defined in claim 8, said elongated device comprising normally vertically 75

disposed upper and lower tubular elements telescopically slideable one within the other to various degrees of extension vertically, the rows of indicia being disposed one on each of the sides of the inner element that is received within the other, the indicia designating leg thicknesses being respectively disposed one on each of the sides of the device on which the rows are positioned, said member comprising a projection extending laterally from a side of the upper element, and said means comprising the end edge of the element

that slidably receives the inner element therein at the end thereof adapted to progressively uncover the sides of the inner element upon extending the device.

10. In a construction as defined in claim 8, means secured to the lower end of said device arranged and adapted to engage the foot of a person and to position the lower end of the device in fixed relation to a predetermined point on any sized and shaped foot. 5

PAUL VERDIER. 10
